UNITED STATES PATENT OFFICE.

MARCUS B. BEHRMAN, OF NEW YORK, N. Y., ASSIGNOR TO LOX SEAL CORPORATION, A CORPORATION OF NEW YORK.

TAG.

1.359.951.

Specification of Letters Patent. Patented Nov. 23, 1920.

Application filed March 24, 1919. Serial No. 284,643.

To all whom it may concern:

Be it known that I, MARCUS B. BEHRMAN, a citizen of the United States, residing at the city, county, and State of New York, 5 have invented certain new and useful Improvements in Tags, of which the following is a specification.

My invention relates to an improvement in tags for attachment to articles of merchandise.

One of the objects of the invention is to provide a tag of simple and improved construction that cannot be removed except by mutilating the tag or its fastener.

15 A further object is to construct the tag of a single piece of material formed with an integral pocket for receiving the ends of the fastener.

It is a matter of common knowledge 20 among merchants that goods are often returned for credit or exchange after having been used. My improved tag is designed to provide an inexpensive device for preventing this abuse of trade. The tag is so constructed that it can be easily attached to an article of merchandise and that when so attached it cannot be removed without mutilation.

The commercial form of my improved tag 30 generally has the legend "This article will not be accepted for credit or exchange if the tag is removed or mutilated" printed on one or both of its faces. Now if the customer undertakes to return the goods without the tag, or with the tag in a mutilated condition, the merchant will have an indication that the goods have been used or handled in an unwarranted manner.

The invention consists in certain novel 40 features of construction and arrangement of parts hereinafter described and particularly pointed out in the claims.

In the accompanying drawings, illustrating 45 a preferred embodiment of the invention,

Figure 1 is a front view of the tag;

Fig. 2 is a view of the blank from which the tag is made;

Fig. 3 is a rear view of the tag;

50 Fig. 4 is a vertical section, on an enlarged scale, through the line 4-4 of Fig. 3;

Fig. 5 is a detailed view of the tip before application to the tie;

Fig. 6 is a detailed view of a tip applied to an end of the tie;

55

Fig. 7 is a modified blank;

Fig. 8 is a plan view of a tag made from said blank, and,

Fig. 9 is an enlarged section through the vertical center line of Fig. 8.

60

The device is made of a single piece of cardboard, paper, metal or other suitable material, which is cut, folded and fastened together, as hereinafter described, so as to form a tag having an integral pocket or receptacle, provided with an eyelet hole for receiving the ends of the fastener by which the tag is attached to the article.

In manufacturing the tag, I cut or die out a blank of substantially the form shown 70 in Fig. 2, the blank being scored transversely to form a body portion 1, an intermediate portion 2 and an end portion 3. An eyelet hole 4, preferably reinforced with a metal gromet, is formed in the blank on the line of fold between the portions 1 and 2, a double line being scored around the eyelet so that, when the portions are folded, the top will have a flat surface adjacent to the eyelet. If desired, a scored or perforated line 5 may be formed across the lower part of the tag body to provide a detachable stub.

The portions 2 and 3 are folded down 85 upon the body portion 1 as shown in Fig. 4, thereby forming a pocket or receptacle. The top and bottom respectively of the pocket being formed by the folds or creases between adjacent portions and the walls of the pockets being formed by said portions. 90 The contacting surfaces of the portions 1 and 3 are preferably pasted together, as seen at Fig. 4.

The sides of the pocket are secured together and the portions are permanently 95 held in their folded position by means of the rivets 6, or other suitable fastening means. This construction provides a pocket to which access cannot be had without mutilation of its parts, except through the eyelet 4 at the top.

In the modification illustrated in Figs. 7 to 9 inclusive, the portion 3 is eliminated and the portions 1 and 2 are made of the same size and shape so that when they are 105 folded upon each other they will register

and give the completed tag a neat and attractive appearance having both faces alike. It will be understood, however, that if desired the portion 2 may be made of different 5 shape and shorter than the portion 1.

The entire surface of one face of the blank is covered with adhesive except at the area, indicated by the dotted circle in Fig. 7, surrounding the eyelet 4. When the blank is 10 folded, as shown in Fig. 9, the portions 1 and 2 will adhere to each other and will form a pocket 9 between them at the place where said portions are free from adhesive. Any suitable means, such as the rivets 6, 15 may be employed, if desired, to reinforce the adhesive and to provide a further safeguard against separation of the portions 1 and 2.

The tag is attached to the object by means 20 of a fastener comprising a flexible tie 7, made of a piece of string, wire, or other suitable material, having a rigid tip 8 at each end. The tips are so formed that they are receivable into the pocket only when inserted vertically through the eyelet and that when thus inserted they are irremovable. This result is attained by making the tip 25 longer than the greatest width of the eyelet and by fastening the end of the tie to the tip at a point intermediate the tip ends, so that the tip, when placed in the pocket, will lie across and underneath the eyelet and thereby prevent removal. In practice it is 30 usual to ship the tags from the factory with one end of the tie fastened in the tag.

The tips 8 may be made of any suitable 35 stiff material. I prefer to make them from sheet metal blanks which are cut substantially in the shape shown in Fig. 5 and are 40 then clamped over the ends of the tie 7 in the manner indicated in Fig. 6.

In compliance with the statutory requirements, I have described and illustrated what I now believe to be the best and most practicable embodiment of the invention, 45 but it will be understood that I do not limit myself to the precise construction shown and described, for I am aware that various modifications and changes may be made therein without departing from the spirit 50 of the invention.

What I claim is:

1. A device of the character described comprising a tag formed of a single piece of material having one portion folded upon 55 another and secured thereto in such manner as to form a hollow receptacle at the top, said receptacle having an eyelet opening, and a flexible tie having a rigid tip secured to each end at a point intermediate the tip 60 ends, said tips being receivable into the receptacle vertically through the eyelet and being longer than the greatest width of the eyelet so as to be irremovable from the receptacle, when inserted therein, except by 65 mutilation of the tag.

2. A device of the character described comprising a tag formed of a single piece of material folded with a double fold and having the folded portions permanently 70 fastened together to form a pocket, the pocket having an eyelet opening, and a flexible tie having a rigid tip secured to each end at a point intermediate the tip ends, 75 said tips being receivable into the pocket vertically through the eyelet and being longer than the greatest width of the eyelet so as to be irremovable from the pocket, when inserted therein, except by mutilation of the tag.

MARCUS B. BEHRMAN.
